Primary Examiner — T. Chase Nelson*Assistant Examiner* — Mark Cavanna(74) *Attorney, Agent, or Firm* — The Small Patent Law Group; Dean D. Small(57) **CLAIM**

The ornamental design of a telemetry transmitter, as shown and described.

DESCRIPTION

FIG. 1 is a front perspective view of a telemetry transmitter showing my new design.

FIG. 2 is a rear perspective view of the telemetry transmitter shown in FIG. 1.

FIG. 3 is another front perspective view of the telemetry transmitter shown in FIG. 1.

FIG. 4 is another rear perspective view of the telemetry transmitter shown in FIG. 1.

FIG. 5 is a front elevation view of the telemetry transmitter shown in FIG. 1.

FIG. 6 is a rear elevation view of the telemetry transmitter shown in FIG. 1.

FIG. 7 is a side elevation view of the telemetry transmitter shown in FIG. 1.

FIG. 8 is another side elevation view of the telemetry transmitter shown in FIG. 1.

FIG. 9 is a top plan view of the telemetry transmitter shown in FIG. 1; and,

FIG. 10 is a bottom plan view of the telemetry transmitter shown in FIG. 1.

The broken lines are included for the purpose of illustrating portions of the telemetry system that form no part of the claimed design.
